Application December 9, 1941, Serial No. 422,224

7 Claims. (Cl. 294—90)

This invention relates to well pipe elevators and the like, and is directed particularly to improvements therein which are calculated to reduce the manual effort involved in applying such devices to and removing them from the pipe.

As is well known to those familiar with oil well drilling operations, it is necessary to periodically remove the string of drill pipe from the well to replace a worn drilling bit. The drill string is separated into sections, or "stands" of from 60 to 90 feet in length, which are racked in an upright position in the derrick. A member of the drilling crew usually termed the derrick man, is stationed on a platform high in the derrick, to unlatch the elevator from the upper end of each stand of pipe as it is disconnected from the drill string and racked in the derrick, and to latch the elevator about each successive stand as the pipe is run back into the well.

The task of the derrick man is most arduous when running the string of pipe back into the well. During this operation, as each successive stand of pipe is connected to the drill string, the drill string is lowered into the well while supported in the elevator, until the upper end of the newly added stand is just above the rotary table. The weight of the pipe is then transferred from the elevator to the pipe slips set in the table, and the elevator is then removed from the pipe and raised in the derrick to pick up the next stand. Meanwhile, the derrick man has moved the next stand into position to be engaged by the elevator. In order to save as much time as possible, the driller at the hoist controls prefers not to decrease the hoisting speed by an appreciable amount as the empty elevator reaches the derrick man, thus requiring the derrick man to grasp the elevator as it approaches his level and draw it toward him and latch it about the pipe while the elevator is travelling upwardly at a substantial speed. It is thus apparent that split-second timing on the part of the derrick man is required. For this reason it is of utmost importance that the elevator hang from the supporting links in such a position that it can be grasped by the derrick man and latched about the pipe with a minimum of effort and in the shortest possible time. The instant invention is directed particularly to this phase of drilling operations.

Well pipe elevators now in use are of two general classes, namely: (1) those in which the supporting ears are formed on diametrically opposite sides of a U-shaped body defining an open-sided pipe recess, and in which the open side of the recess is closed by a door or gate pivotally

5 mounted on the body on an axis at one side of the open recess, this type being generally referred to as "side-door" elevators; and (2) those comprising two substantially symmetrical sections meeting in a diametric plane extending at right angles to the plane of the supporting ears, and being hingedly connected at the rear side of the pipe recess and releasably latched together at the front side. This type is usually referred to as "center latch" or "double door" elevators.

10 It is characteristic of center latch elevators that as the sections are swung outwardly relative to each other about their pivotal axis, the rear portion of the elevator moves toward the vertical plane of support extending through the supporting ears, thus shifting the center of gravity of the elevator forwardly of that plane. This creates a tendency for the front side of the elevator to tilt downwardly to an extent to again dispose the center of gravity in the aforesaid plane of support. This tilting movement is an advantage in one respect for the following reason. Inasmuch as the supporting ears are each formed on one of the elevator sections, the opening movement of the sections increases the distance between the ears, thus causing the elevator links to assume downwardly diverging positions with respect to each other. The tendency of the links to return to their normal suspended 15 positions tends to close the elevator if the links are both suspended from a single hook, and, even if the links are separately suspended at laterally spaced points on a multiple hook, the closing tendency is usually sufficient to prevent the elevator from remaining fully open unless it tilts downwardly in front. It will be apparent, however, that when the front portion of the elevator is tilted downwardly to dispose the pivotal axis in an inclined position, the weight of the elevator constitutes a force, one component of which exerts a turning moment about the pivotal axis in opposition to the closing force exerted by the links.

20 For the foregoing reasons, it has been customary to allow center latch elevators to "break down," or tilt downwardly in front, in order to maintain them in open position while being raised in the derrick to pick up a stand of pipe. This practice has the disadvantage, however, of requiring the derrick man to tilt the elevator back to upright, or nearly upright, position in order to align the pipe bore of the elevator with the pipe before the elevator can be latched on the pipe.

25 The instant invention has as its principal ob-

ject the provision of an elevator having an improved balancing arrangement, particularly for a center latch elevator, whereby the elevator when in open position will hang in the most favorable position for quickly and easily applying it to the pipe.

A further object is to provide, in conjunction with the aforesaid balancing arrangement, means for releasably maintaining the elevator in open position.

A still further object is to provide means for normally preventing objectionable tilting of an elevator, which means will permit the elevator to be tilted when desired.

A still further object is to provide elevator balancing means which is adjustable at will to maintain the elevator, when it is open, either in upright position or inclined in either direction by any desired amount.

A still further object is to provide an elevator having means incorporated therein for exerting a force yieldingly maintaining the elevator in open position, the arrangement being such as to require not only slight manual effort to effect the initial closing movement of the elevator sections, and the aforesaid force being rendered inactive upon such initial closing movement.

A still further object is to provide elevator balancing and spreading means which may be applied to elevators now in use without altering their design.

The manner in which the foregoing and other objects are attained will be apparent from the foregoing detailed description of a preferred embodiment of the invention and a modification thereof, reference being had to the accompanying drawings wherein:

Fig. 1 is a fragmentary elevational view of the upper portion of an oil well derrick in the region of the derrick man's platform, illustrating the position of a stand of pipe about to be picked up, in accordance with one form of practice widely used, and showing the elevator in tilted position just prior to being latched on the pipe;

Fig. 2 is a view generally similar to Fig. 1, but illustrating the position of a stand of pipe when a fingerboard is used, the elevator being shown as equipped with balancing means in accordance with the invention;

Fig. 3 is a fragmentary view adjacent the derrick floor, illustrating the inclination which the elevator must assume with respect to the links when picking up or laying down a stand of pipe;

Fig. 4 is a perspective view of an elevator and set of links equipped with our preferred form of balancing means;

Fig. 5 is a top plan view of the elevator shown in Fig. 4, the major portion of the figure being taken substantially on line V—V of Fig. 4, and the rear portion of the elevator being broken away on substantially the line V—V of Fig. 7 to illustrate details of a preferred form of yieldable spreading means;

Fig. 6 is a view similar to Fig. 5, but showing the elevator in closed position;

Fig. 7 is a vertical view taken on line VII—VII of Fig. 5, showing the yieldable spreading means in elevation;

Fig. 8 is a perspective view, on an enlarged scale, of the balance strap shown in Figs. 4, 5 and 6;

Fig. 9 is a front view of an elevator similar to that shown in Fig. 4 but equipped with an alternative form of spreading means;

Fig. 10 is a rear view of an elevator, illustrating still another form of spreading means.

In order to clearly illustrate the variety of conditions under which the elevator must be applied to and removed from a stand or section of drill pipe, there are shown, in Figs. 1, 2 and 3, three typical operating situations. In Fig. 1, the stand of pipe 1 is inclined away from the center line of the derrick 2, being temporarily supported in its nearly upright position by resting either against the inner edge of the derrick man's platform 3, as shown, or alternately supported by the derrick man standing on the platform. This practice prevails when no "fingerboard" is used. 15 The elevator 4, suspended by the usual links 5 attached to the drilling hook 6, is being raised in the derrick in open position preparatory to being latched around the pipe 1. It will be observed that the forward side of the elevator is tilted downwardly to maintain the elevator open, as previously explained. When the elevator comes within reach of the derrick man, he grasps the handles 7 and tilts the elevator upwardly while drawing it toward the pipe, and finally 20 latches it around the pipe. Inasmuch as the elevator is being raised by the hoisting mechanism during this time, it is apparent that the derrick man must act very quickly in order to raise the forward side of the elevator more rapidly than the bodily movement of the elevator as a whole. 25 The amount of tilting movement required to align the bore of the elevator with the pipe is, of course, less when the pipe inclines outwardly, as in Fig. 1, than when it inclines inwardly, as 30 shown in Fig. 2. However, even under the former, more favorable condition, the operation of raising the forward side of the elevator to align it with the pipe imposes an arduous task on the derrick man and tends to slow down the 35 operation.

In accordance with another widely used method of handling drill pipe in the derrick, a fingerboard 10 is mounted in the derrick in a position parallel to the inner edge of the fourble board 45 and spaced inwardly therefrom, as shown in Fig. 2. The fingerboard and the inner edge of the fourble board define a recess open at one end, into which the upper ends of the stands of pipe are successively inserted, the fingerboard 50 serving as a temporary support for the upper end of the stand. It is customary to mount the fingerboard as close as possible to the center line of the derrick without interfering with the vertical travel of the travelling block, hook, links 55 and elevator, and consequently a stand of pipe leaning against the fingerboard is inclined inwardly at its upper end, as shown in Fig. 2. It will be apparent, therefore, that if the elevator should be raised in the derrick in the inclined 60 position shown in Fig. 1, the derrick man would be required to tilt it upwardly through a very considerable angle in order to align it with the pipe when the latter is inclined inwardly as in Fig. 2. To overcome this difficulty, we have provided means, shown herein in the form of a balance strap generally designated 12, for maintaining the elevator in proper position to be applied to the pipe without tilting its forward side upwardly. The construction of the balance strap 65 and its attaching means will be described in detail hereinafter. 70 As the drilling of the well proceeds, it is necessary to add sections of drill pipe to the drill string from time to time. It is customary to pick 75 the new sections up from the derrick floor by

the elevator 4, in the manner shown in Fig. 3. Also, when laying down sections of drill pipe, as when a change is made to a different size of pipe, the elevator is required to tilt with the pipe into the position shown in Fig. 3. It is thus apparent that the elevator must frequently be tilted at nearly right angles to the links, and hence any balancing means provided for normally maintaining the elevator in upright position must be capable of permitting tilting thereof when desired.

Referring now to Figs. 4 to 8 inclusive, we have shown our novel balancing means as applied to a well-known type of elevator 4 such as is used for handling external upset drill pipe—that is, pipe having a tapered upset at the base of the tool joint. The elevator comprises generally a pair of sections 15 and 16 pivotally interconnected at the rear side by a hinge pin 17, and having a latch 18 for detachably securing the forward sides of the sections together about a pipe. Semi-circular bores 19 and 20 are formed in the inner walls of the respective sections and cooperate to form a circular pipe recess when the sections are closed. As most clearly shown in Fig. 7, a downwardly tapered seat 21 is formed in the bore, and conforms to the tapered upset 22 on the pipe 1 (Figs. 1 and 2), to support the pipe in the elevator. Each section is provided with a pair of outwardly projecting upper and lower ears 23 and 24 defining link recesses in which the lower eyes of the elevator links 5 are received and releasably confined by detachable retainer blocks 25. A pair of handles 7 project outwardly from the forward sides of the sections and a handle 26 is formed at the rear side of one section, to aid in the manual manipulation of the elevator. For a more complete description of the detailed construction of the elevator, reference is made to U. S. Letters Patent No. 2,067,663 to Herbert E. Grau, dated January 12, 1937.

Referring now to our novel elevator balancing means, it will be observed that a tension member, shown herein in the form of a strap 12, is connected at one end to the forward side of the elevator section 16 and at its other end to the shank portion of the corresponding link 5. Insofar as the principal function of the strap is concerned, it may obviously assume various forms and having varying characteristics. We prefer, however, that it be flexible and also resilient in the direction of its longitudinal axis, to cause it to exert a predetermined lifting force on the forward side of the elevator, but at the same time be capable of yielding to permit the elevator to tilt when such tilting is desired—as, for example, when picking up or laying down a section of drill pipe. We have found that a strap composed of rubber, "Neoprene," or other resilient material is entirely satisfactory, although it would be feasible to employ a coiled extension spring if desired. A non-extensible, flexible member, such as a length of cable or chain, may also be employed, but in that case it would be necessary to detach one end when laying down or picking up pipe.

As shown most clearly in Fig. 8, the preferred form of balance strap 12 comprises a strip of rubber "Neoprene" or the like, preferably rectangular in cross-section. An end link 30 of a short series of chain links is attached to one end of the strap, either by molding it therein if the strap is molded to shape, or by inserting the ends thereof in a hole formed in the strap, if the latter is cut from sheet stock. A T-shaped

clip 31 is attached to the opposite end of the strap, and is adapted to be inserted through a hole formed in the elevator for that purpose, preferably in the right-hand handle 7, as indicated at 32 in Figs. 4, 5 and 6. The opposite end of the strap 12 may be attached to the link 5 in any suitable and convenient manner. By way of example, we have shown a T-head 32 on the end of the strap, formed by recessing the opposite edges thereof at 33 and 34. A split clamp 35 is secured to the link 5, and is provided with a U-shaped clip 36, either formed integral with the clamp or secured thereto as by riveting, and having a pair of spaced tabs between which the neck portion of the T-head 32 on the strap is adapted to be retained. The arrangement is such that the strap may be readily attached to or removed from the clamp by slight manual distortion thereof, but is firmly held against inadvertent release.

As is most clearly shown in Fig. 4, it has been found advantageous to wrap the strap at least one turn about the shank of the link, whereby the frictional engagement of the strap with the link reduces the stress on the T-head 32 and on the clip 36. Inasmuch as the shank of the link is circular in cross-section, and of substantially constant diameter, the clamp 35 may be adjusted both angularly about the shank and vertically along the shank to cause the elevator to be held in any desired position when open. In this manner, when the elevator is to be used on a drilling rig having no fingerboard, as in Fig. 1, the clamp may be so adjusted on the link as to cause the strap to maintain the elevator in a slightly downwardly inclined position with its bore parallel to the stand of pipe. On the other hand if the elevator is to be used on a drilling rig equipped with a fingerboard so that the stands of pipe are inclined inwardly when the elevator is applied thereto, as in Fig. 2, the clamp 35 may be adjusted to a higher position on the link or rotated in a clockwise direction to wrap more of the strap around the shank of the link, and thus cause the strap to maintain the elevator with its bore parallel to the pipe.

As set forth in the introductory remarks, an elevator of the center-latch type tends to close due to the spreading of the links outwardly of their normally suspended positions. It is therefore desirable to provide, in conjunction with the above-described balancing means, other means resisting this closing tendency. Various expedients may be employed for this purpose, but we have found that most satisfactory results are obtained by the use of a spring-pressed detent or catch which may be rendered inactive by slight manual pressure on the elevator handles in closing direction.

Referring to Figs. 5, 6 and 7 of the drawings, it will be observed with particular reference to Fig. 7 that the bore of the elevator body is enlarged between the upper bore 19 and the lower centering rib 40, providing recesses 41 and 41a in the respective elevator sections 15 and 16, one of which recesses forms a convenient place for mounting a spring detent 42. The detent comprises a flat, elongated bow spring, the free end of which is rounded over at 43 to provide a cam surface 44. The opposite end of the spring is turned outwardly at 45 and engages a slot 46 formed in a retainer plate 47 welded or otherwise secured to the wall of the recess 41 in the elevator section 15. The outer wall of the retainer plate is grooved lengthwise thereof from the slot

46 to the remote end of the plate, to receive the spring 42 and retain it firmly in place.

As shown most clearly in Fig. 7, the hinge pin 17, which pivotally connects the two body sections together, extends through upper and lower hinge lugs 50 and 51 on the body section 15 and a central hinge lug 52 on the body section 16. A cam projection 53 is formed on the central hinge lug 52 in the horizontal plane of the spring 42, and is provided with a forward, steeply pitched cam surface 54 and a rear cam surface 55 of relatively flat pitch (Fig. 6). A relatively wide clearance is provided at 56 (Fig. 5) between the hinge lug 52 and the adjacent wall of the body section 15, to receive the projection 53 when the body sections are closed.

It will be observed that the outward flexing of the spring detent 42 is limited by engagement thereof with the wall of the recess 41, and it will be noted in particular, with reference to Fig. 6, that a slight clearance is provided between the curved-over end 43 of the detent and the wall of the hinge lug 52. Thus the only frictional engagement between the detent and the hinge lug is during the time the detent engages the cam projection 53. In this manner, frictional wear on the detent and hinge lug is reduced to a minimum, and the detent is wholly inactive once it has been disengaged from the projection and hence it offers no resistance to closing of the elevator after the initial closing movement has been effected.

The operation of the spring detent will be apparent from the foregoing description. When removing the elevator from the pipe, the sections are spread apart as far as permitted by the usual opening stops (not shown) on the body sections. This opening movement is slightly more than sufficient to cause the cam projection 53 to pass to the right of the curved end 43 of the spring, to the position shown in Fig. 5. In passing the spring end, the cam surface 55 on the projection engages the curved cam surface 44 on the spring and flexes the spring outwardly. Because of the relatively flat wedge angle of the cam surface 55, the flexing of the spring offers no substantial resistance to opening movement of the elevator sections. However, when the steeply pitched cam surface 54 on the opposite side of the projection engages the spring end, the force required to flex the spring inwardly is considerably greater. By suitably shaping the cam surface 54 and by the selection of a spring of proper strength, the resistance offered thereby may be such as to only slightly exceed the closing force exerted on the elevator by the links. Hence, upon application of slight manual pressure on the elevator handles 7 in a closing direction, the spring may be flexed inwardly to allow the projection 53 to pass it. After the projection has passed the spring, the closing of the elevator is effected without interference by the spring.

In Fig. 9 there is shown an elevator 4' generally similar to the elevator 4 of Figs. 4, 5, 6 and 7 and equipped with a balance strap 12, but embodying an alternative means for yieldingly maintaining the elevator sections spread apart. In this embodiment, the central portion of the male hinge lug 52' on the body section 16' is removed to provide space for a torsion spring 60 encircling the hinge pin 17'. The opposite ends of the spring bear against the respective body sections 15' and 16', yieldingly urging them apart, but permitting closing of the elevator upon ap-

plication of sufficient manual pressure on the handles 7' in closing direction. This arrangement is effective for the intended purpose, but is less desirable than the spring catch shown in Figs. 5, 6 and 7 for the reason that the force required to overcome the spring pressure increases as the elevator sections approach closed position. In the preferred embodiment, on the other hand, no resistance to closing movement is offered after the cam projection 53 has passed the curved head 43 on the spring.

In Fig. 10, another alternative form of spreading means is shown. In this instance the opposite ends of an extensible and resilient member 15 such as a strap 62 of rubber or the like, similar to the balance strap 12, is attached in any suitable manner to the outwardly extending ears 63 and 64 on the respective elevator body sections 65 and 66, and extends around the hinge lugs 20 at the rear side of the elevator. In this manner, when the elevator is closed the strap is extended and stressed, and exerts a force tending to open the sections. The ends of the strap may be conveniently attached to the ears 63 and 64 by providing a hole in each end thereof through which extend the bolts 67 and 68 which releasably secure the link-retaining blocks 69 and 70 in place. This form of spreading means has been found to be entirely satisfactory, and is exceedingly simple and inexpensive. It can be more easily applied to an elevator than the torsion spring 60 of Fig. 9, which requires removal of the hinge pin 17' to install the spring. However, the spreading strap 62 of Fig. 10 is subject to the same objection as the torsion spring—namely, it is increasingly stressed as the elevator sections approach closed position, and hence requires the application of increasingly greater manual force to close the elevator.

From the foregoing description of a preferred embodiment of the invention and two modifications thereof, it will be apparent that relatively simple but highly effective means have been provided for insuring that the elevator is maintained in proper position to enable the derrick man to quickly and easily apply it to the pipe by simply drawing it toward him, without having to tilt it into alignment with the pipe. The balancing means is adjustable to permit the elevator to be suspended in any desired position, to meet varying field practice, and in the preferred embodiment the resilient balance strap permits tilting of the elevator when desired, without disturbing the connection between the strap and the elevator or the link.

The provision of means for releasably maintaining the elevator sections in open position, in conjunction with the balancing means, not only insures proper alignment of the elevator with the pipe but also prevents inadvertent closing of the elevator due to vibration or swaying as it ascends or descends in the derrick. It will be appreciated, however, that it may not be necessary in all instances to provide the spreading means, and that the balancing means may alone be used if the particular elevator on which it is used does not tend to close when held in upright position. It will also be appreciated that in some instances the spreading means may be used without the balancing means, if the construction of the elevator is such that it does not tend to "break down" when open.

It will be apparent to those skilled in the art that the novel balancing and spreading means

may assume various forms, and it is to be understood that the forms shown and described herein are solely for illustrative purposes. Hence the invention is not limited to the precise form shown herein, but is of the full scope of the appended claims.

We claim:

1. In a well pipe elevator, the combination of: a pair of body sections cooperating to define a pipe-receiving bore, means pivotally connecting said sections together for relative horizontal swinging movement, latch means for releasably connecting the free ends of the sections together, a pair of supporting links each pivotally supporting a respective body section for tilting movement about a transverse axis, and a resilient tension member connected at one end thereof to one of said links at a point offset vertically from said transverse axis and having its other end connected to one of said body sections at a point offset laterally from said transverse axis. 10
2. In a well pipe elevator, the combination of: a pair of body sections cooperating to define a pipe-receiving bore and being pivotally connected for relative horizontal swinging movement, latch means for releasably connecting the free ends of the sections together, link means pendently supporting the elevator for tilting movement about a transverse axis, and means normally resisting such tilting movement and comprising a resilient tension member extending between said link means and one of said body sections, said tension member being adapted to yield upon application of an external force tending to tilt the elevator about said transverse axis. 25
3. In combination, a well pipe elevator of the type comprising a pair of pipe-encircling sections pivotally interconnected for relative swinging movement about a normally vertical axis into open and closed positions, suspension means pivotally supporting said elevator for tilting movement about a transverse axis, said sections being so related to each other and to said suspension means that relative pivotal movement between the sections changes the center of gravity there- 30
4. In combination with a well pipe elevator and a pair of elevator supporting links from which the elevator is suspended, a flexible, resilient tension member connected at one end thereof to one of said links and connected at its other end to said elevator at a point offset laterally from the vertical plane of supporting connection of the elevator with the links. 35
5. In combination with a well pipe elevator and a pair of elevator supporting links from which the elevator is suspended, a flexible, resilient tension member adjustably connected at one end thereof to one of said links and having its other end connected to said elevator at a point offset laterally from the vertical plane of supporting connection of the elevator with the links. 40
6. In a well pipe elevator for use with a pair of supporting links, a pair of sections connected at one end, supporting means on each of said sections forwardly of said pivot and offset laterally from the bore of the elevator whereby opening movement of the elevator sections causes said pivot to move forwardly with respect to the plane of said supporting means, thereby causing the elevator sections to tend to tilt forwardly, resilient means interposed between said supporting means and one of said sections for yieldingly restraining said tilting movement, whereby said elevator sections tend to move toward the closed position, and means acting between said sections to yieldably resist said closing movement. 45
7. A device as set forth in claim 6 in which said closing-resisting means is effective only during the initial closing movement of said elevator sections when in the fully open position.
